DESIGN FOR A SHOE RACK

Charles Harvey Churchill, Cortland, N. Y.

Application March 10, 1944, Serial No. 112,839

Term of patent 14 years

(Cl. D80—9)

To all whom it may concern:

Be it known that I, Charles Harvey Churchill, a citizen of the United States, residing at Cortland, in the county of Cortland and State of New York, have invented a new, original, and ornamental Design for a Shoe Rack, of which the following is a specification, reference being had to the accompanying drawings, forming part thereof.

Fig. I is a front perspective view, and Fig. II is a rear perspective view of a shoe rack, showing my new design.

I claim:

The ornamental design for a shoe rack, as shown.

CHARLES HARVEY CHURCHILL.
